ISRAEL HOGELAND, OF INDIANAPOLIS, INDIANA.

Letters Patent No. 84,694, dated December 8, 1868.

IMPROVED CLOTHES-RACK

The Schedule referred to in these Letters Patent and making part of the same.

To all whom it may concern:

Be it known that I, ISRAEL HOGELAND, of Indianapolis, in the county of Marion, and State of Indiana, have invented a new and improved Clothes-Rack; and I do hereby declare that the following is a full, clear, and exact description thereof, that will enable skilled artisans to make and use it, reference being had to the accompanying drawing, making part of this specification.

This invention consists in pivoting one end of the cross-bars of a rectangular clothes-frame to one of the side-pieces of the frame, and providing a device by which the other end of such cross-bars can be readily attached to or detached from the opposite side-piece, so that the whole apparatus can be folded into a more compact form than heretofore.

Figure 1 is a side elevation of my improved clothes-drier, when set up and arranged ready for use.

Figure 2 is a front elevation of the same.

The same letters indicate the same parts in both figures.

The frame of the drying-rack is composed of the side-pieces A, the horizontal brace-pieces B, and the legs C. The brace-pieces B are pivoted at one end, by screws, to the side-pieces A, and the other end is dovetailed, to fit into corresponding notches in pieces D, attached to the side-pieces A, and arranged as shown, so as to be conveniently folded against them.

Hooked rods, E, are attached to the lower bar B, that hook over pins near the foot of the side-pieces; also serve to brace the frame.

The inside edges of the side-pieces A are furnished

with eyes, F, through which to pass the line G, from side to side of the frame.

The frame is supported in an inclined position by legs C, which are pivoted to the side-pieces, so as to fold against them. The legs are stayed from getting out of place by chains or linked rods I, as shown in fig. 1.

By arranging the rack to set at an inclination, as shown, the clothes hang apart, so as to allow a free circulation of air among them, and by this arrangement I am also enabled to set the rack close to and with its upper end projecting over the stove, by which the clothes will be more rapidly dried.

When the rack is not in use, the horizontal bars B and legs C may be folded alongside the pieces A, and the line rolled around them, thereby reducing it to a compact form, occupying but little space, and convenient for storing away.

I do not broadly claim a clothes-drier, having folding legs C; nor do I claim the employment, in a clothes-rack, of the cords G G; but

What I do claim as my invention, and desire to secure by Letters Patent, is—

In a rectangular clothes-frame, the two rigid stays or cross-bars B B, pivoted, at one end, to one of the side-pieces, A A, and having the end which is not pivoted attached to the opposite side-piece, in such a manner that it is easily detachable, substantially as described and for the purpose specified.

ISRAEL HOGELAND.
